UNITED STATES PATENT OFFICE.

ADOLPH K. MALMQUIST, OF SOUTH BELLINGHAM, WASHINGTON, ASSIGNEE, BY MESNE ASSIGNMENTS, TO THERMOKEPT CORPORATION, OF NEW YORK, N. Y., A CORPORATION OF DELAWARE.

CANNING APPARATUS.

Application filed March 18, 1925, Serial No. 16,431, and in Canada March 21, 1924.

This invention relates to improvements in 5 canning machinery, and more particularly to mechanism for shaping or perfecting the open end portions of cans,—one object of the invention being to provide efficient mechanism which shall operate automatically on cans fed thereto successively to properly shape or perfect their open end portions, preparatory to feeding the cans into and 10 through vacuumized chambers wherein the cans and their solid contents may be subjected to vacuum.

With this and other objects in view, the invention consists in certain features of construction and combinations of parts as hereinafter set forth and pointed out in the claims.

In the accompanying drawings:

Figure 1 is a view in vertical section illustrating my improvements;

Figure 2 is a view partly in plan and partly in section;

Figures 3, 4 and 5 are vertical sectional views illustrating different positions which 25 the movable parts will be caused to assume during the operation of the machine, and Figures 6 to 10 illustrate details.

Mounted upon a suitable support 1 is a bracket 2, on which the framework of the 30 shaping mechanism is supported. This framework includes an upper bracket 3 located above the lower bracket 2 and sustained by an upright bracket 4. Cans may be fed to the machine by a suitably rotated table 5, and upon their discharge, the cans may pass over a table 6 on their way to a chamber indicated at 7 wherein the cans and their contents may be subjected to treatment. The means employed for feeding the 35 open cans into the shaping or perfecting mechanism and also from such mechanism to the chamber 7, may be substantially such as shown and described in my co-pending applications filed respectively, on the 18th day of August, 1922, and on the 26th day of August, 1924, and designated respectively by Serial No. 582,712 patented October 4, 1927, No. 1,643,990, and Serial No. 734,223 patented October 12, 1926, No. 1,603,132 and 45 50 need no further description herein, as the present improvements relate particularly to the can shaping or perfecting mechanism.

When a can is moved into the can-perfecting mechanism, it will become deposited

upon one of a series of can supporting platforms or pockets 48, each of which is made with a lateral extension 49 to facilitate the subsequent discharge of the can and each of said platforms or pockets is made with a groove 50 for the accommodation of the bottom flange of a can. The platforms or pockets 48 are provided with depending shanks 51 entering sockets in the upper ends of plungers 52 and pinned to the latter, as at 53. The plungers 52 are vertically movable through suitable holes in arms 54 on a spider 29 secured to and rotatable with a shaft 30, and each platform or pocket 48 is made with an extension 55 which carries a guide rod 56 entering a hole 57 in one of the spider arms 54. Each plunger 52 carries near its lower end, a roller 58 to cooperate with a grooved cam 59 secured to the lower fixed bracket 2, for raising and lowering the platform or pockets and the can 70 thereon relatively to the devices located above the same which operate to straighten or perfect the open flanged upper ends of the cans, all as shown and described in my co-pending applications, hereinbefore identified.

The can raising and lowering devices and the straightening or perfecting devices above referred to constitute one of units 60 of the can perfecting mechanism, and in the apparatus illustrated in the drawings, six such units are employed, and the movable parts of each of said units are carried by the spider 29. In addition to the radial arms 54, the spider 29 is provided with a horizontal plate or bracket member 62 located above the said arms and provided with openings 63 and seats 63^a for the accommodation of the upper ends of cans when the same are raised by the raising of the can platform or pockets 48. The driving shaft 30 for the spider 29 passes through the central tubular portion of the latter and is pinned to the same,—the upper portion of said shaft passing through a bushing 65 in a bearing 66 on the upper bracket 9. The lower portion of the shaft passes through a bushing 67 in the enlargement 61 on the lower bracket 2 and a gear 68 is keyed to its depending end,—ball bearings 69 being interposed between said gear and the lower bracket 2 and enclosed by flanges 70 and 70^a. The gear 68 is driven by suitable means as shown

and described in my copending applications previously identified.

Each unit 60 of the straightening or shaping mechanism includes a flanging punch 87, and shaping dies 88, 89, the latter being slidably mounted on the bracket 62 and under a portion of said bracket, rollers 90 are located to assist in supporting the spider 29 during the flanging operation of the 10 punch 87. The flanging punches 87 for the several units 60 are carried by a bracket 91 which is rotatable on the bushing 65 and is rotatable with the spider 29. The head of each punch 87 may be made dish-shaped and 15 provided with a depending annular flange 92 (Figure 8) to engage the flanged edge of a can. Each punch head is provided with a central shank 93 to enter a socket 94 in the lower end of an arm or carrier 95 and 20 from said shank, a threaded stem 96 projects and enters a threaded portion of the socket 94. This construction permits the punch head to be adjusted vertically, and it may be held at any desired adjustment by a 25 spring latch 97 which may engage in any one of a series of notches 98 in the edge of the punch head. A laterally projecting pin 99 is carried by the upper portion of the arm or carrier 95 and on this pin, a roller 100 is mounted and cooperates with a cam 101 on the under side of the fixed bracket 3, —said cam being adapted to cause vertical movement of the punch during rotation of the bracket 91 and spider 29 about the 35 shaft 30. The sliding dies 88 and 89 of each unit 60 are caused to approach and recede from the can, by the action of fixed cams 102 and 103, —each die 88 being provided with a roller 104 to cooperate with the 40 cam 102, and each die 89 being provided with a roller 105 to cooperate with the cam 103.

When a can shall have reached one of the platforms or pockets 48 of one of the can 45 perfecting units 60, the parts of said unit will be in the position indicated at the left hand side Figure 2 and as shown in Figure 3. As the spider 29 rotates and the roller 58 travels on the cam 59, the platform or pocket 48 will be raised so that the upper flanged end of the can will be projected through one of the openings 63 of the spider 62 and about one-eighth of an inch above the plane of the jaws or dies 88—89. During 55 the same extent of travel of the unit 60, co-operation of the roller 100 with the upper cam 101, will cause the sleeve or carrier 95 and hence the punch head 87 to descend and its circular flange 92 to enter the open upper 60 flanged end of the can. At the same time the jaws or dies 88—89 will be caused by the cams 102—103 to move toward each other and engage the upper edge portion of the can. The positions of the parts will 65 then be as indicated in Figures 4 and 5. The

raising of the can sufficiently to cause its flanged upper end to project slightly above the plane of the dies is of importance because the flanges of some cans are badly bent and if not raised above the plane of the dies, 70 the latter might catch the flange and fail properly to clear the same as the spider continues to rotate carrying the can with it. During the travel of the spider roller 58 will enter a depressed portion 106 of the 75 cam 59 (Fig. 7) and the can will then hang on the dies and the flange of the can may be shaped without changing the height of the can. During the travel of the parts from this point, roller 100 cooperating with 80 the cam 101, will cause the arm or sleeve 95 and punch head 87 to move downwardly and the punch head to be moved down tightly against the can flange and the latter to be straightened or its shape perfected. In 85 order that the can flange may be kept straight or properly shaped, it is important that the punch be given a sudden hammer blow, otherwise the can flange might spring back to its original shape after having been 90 released from the action of the punch and dies. To accomplish such a blow being imparted to the punch at the proper time and the parts approach the positions shown in 95 Figures 4 and 5, a yielding cam is provided at 107 (Figure 6) to be engaged by the roller 100. By permitting the cam 107 to yield slightly when it is engaged by the roller 100 any slight inequalities in the thickness of the tin of the can flange or the 100 presence of solder may be compensated for without damage to the tin of the flange. The upper, open flanged end of the can having now been straightened or perfected in shape, the dies and the flange punch will 105 recede and the can will descend with the descent of the can carrying platform 48 during the travel of the unit 60 and the perfected can is ready to be transferred to the chamber 7 wherein the filling of the can 110 with liquid, such as syrup, may be performed, and in the meantime, other cans have been perfected in the mechanism as the spider 29 thereof continues to rotate.

Having fully described my invention what 115 I claim as new and desire to secure by Letters-Patent, is:—

1. In apparatus for correcting the shape of the open ends of cans, the combination with frame work and a rotating spider having arms each provided with a vertically movable can support, and a vertically movable punch above said support and adapted to engage the open end portion of a can on said support, of horizontally disposed sliding shaping dies to engage and embrace the open end portion of the can and correct any irregularity thereof, and cam means for sliding said dies relatively to each other and relatively to a can. 120 125 130

2. In apparatus for correcting the shape of the open upper ends of cans, the combination of shaping dies with a rotating spider, and means for operating the same, a punch 5 to enter the mouth portion of a can, a vertically movable support for the punch, means for effecting vertically adjustable connection of the punch to said support, and means for locking the punch at different positions 10 of adjustment relatively to its support.

3. In apparatus for correcting the shape of the open upper ends of cans, the combination of a vertically movable can platform, can shaping devices above said platform, and 15 a cam having a raised portion for causing said platform to move vertically, said raised portion having a recess.

4. In apparatus of the character described, the combination with framework and a rotating spider, of a plurality of can shape 20 perfecting mechanisms carried by said spider, each of said mechanisms comprising a vertically movable can support, a vertically movable plunger over said support, a punch head carried by said plunger, means 25 for adjusting each punch head vertically, relatively movable dies to engage a can, cam means for operating said dies, means for reciprocating said can supports and means for reciprocating said plunger. 30

In testimony whereof, I have signed this specification.

ADOLPH K. MALMQUIST.
